UNITED STATES PATENT OFFICE.

CHARLES JOSEPH RHODES, OF WAKEFIELD, ENGLAND.

FLANGING AND SEAMING OF SHEET-METAL RECEPTACLES.

Application filed August 2, 1927, Serial No. 210,030, and in Great Britain January 6, 1927.

This invention relates to apparatus for automatically flanging and seaming sheet metal receptacles for example the attachment of an end or ends, or base or cover to sheet metal drums of cylindrical and other regular section and of that type which includes two headstocks or the like embodying axially aligned chucks or equivalents between which the work is held and rotated and there acted upon by suitably shaped tools conveniently in the form of rollers by which the flanging and seaming operations are successively performed either at one end or at both ends of the work simultaneously.

15 An example of such apparatus is disclosed in my Patent No. 1,643,470 issued to me September 27, 1927, the application for which patent was co-pending with the present application to which reference is directed and 20 in which the various rollers for performing the operations of flanging, curling and flattening the metal joints are independent of each other, the flanging roller or rollers being located in the vertical axial plane of the 25 machine and the curling and flattening rollers on opposite sides of said axial plane respectively but movable on paths converging toward said axial plane, all said rollers being operated by separate cams carried by 30 shafts disposed on opposite sides of said axial plane.

According to the present invention the same general arrangement of rollers or tools as just described may be retained as regards their relation to the axial plane of the machine and cam operation but all said rollers and their operating mechanism including cams, cam shafts etc. are positioned overhead, or above the horizontal axis of the 35 chucks which are placed low down or close to the bed or base of the machine. Such a construction presents the important advantage that scale or the like which may fall from the work during the flanging and seaming operations does not engage or foul any of the working parts but may be delivered directly to the ground or to the base of the machine from which it may be readily removed.

40 According to the invention also means are provided for easily feeding the work between the chucks, such means comprising a tilting or movable skid or table arranged at one side and suitably curved or inclined downwards 45 towards the ground so that the work may be

rolled up and along same to a depression or recess below the axis of the chucks. This table or skid is adapted to be operated by a treadle or equivalent and intermediate connections to raise the work into proper position between the chucks, whereupon one or both of the latter is or are adjusted or moved to grip the work between them. After completion of the operations the chuck is withdrawn allowing the work to be released and lowered again onto and by the table or skid. An inclined or curved portion of this table or skid, or a separate table, extends to the other side of the machine to facilitate removal of the finished receptacles.

Such removal of the finished receptacles from between the chucks is however assisted by stripping means designed to obviate any tendency of the drums to stick to the chucks. Such stripping means suitably comprise for each chuck a double armed lever having at the outer end of one arm a roller or equivalent adapted to engage the end of the receptacle, said levers being so interconnected and automatically operated at the required times that the oppositely disposed rollers each pertaining to a chuck are forced towards one another and strip the finished article from the chucks. By the provision of the feeding and stripping means described it will be apparent that rapidity of operation is promoted, thus increasing the output of the machine.

45 A further feature of the present invention consists in the operation of one of the chucks with its associated working rollers or tools by fluid pressure such as that of steam or compressed air whereby said parts are operated with great ease and which compensates for slight variations of length of the work which occurs in practice (assuming the chuck 50 has been set for work of a given size). The movable head-stock with the chuck and rollers are adjustable longitudinally of the machine as a unit for work of different sizes and the chuck and rollers are adjustable or movable independently of the head-stock for insertion and removal of the work and in carrying out the fluid operation feature of the invention a convenient method is to mount a 55 steam or air cylinder on the adjustable head-stock the piston of said cylinder being under control of a suitable hand lever and the piston rod coupled to the movable chuck-supporting slide or head by means of a toggle system or parallel lever motion. Such move- 60

ment of the chuck slide may also be caused automatically to operate the work stripping means above described.

In connection with the flanging rollers associated with opposing chucks there may be provided an adjustable tie rod for the purpose of taking up a certain amount of inward thrust or deflection on the flanging roller spindles. The said tie rod is adjustable so that receptacle bodies of different lengths or depths can be accommodated and its presence will provide for longer life of the flanging roller spindles.

Any appropriate mechanism may be employed for operating and controlling the moving parts of the machine, but the following are suitable arrangements for a practical embodiment. The machine may be driven from an electric motor through a friction clutch and brake manually controlled as by a hand starting lever and on a main drive shaft passing centrally through, and enclosed by, the base of the machine, this shaft extending the whole length of the machine and at the opposite end driving a train of gearing mounted on the fixed frame or tail-stock and operating two upper cam shafts disposed on opposite sides of the axis of the machine and carrying the cams for actuating the various working rollers or tools. The starting lever is adjustably coupled to another clutch device associated with the cam shafts so that when the latter have performed a certain number of revolutions corresponding to a complete operation of the machine the hand lever is actuated to stop the machine or alternatively this may be performed by manipulating the hand lever itself. The chuck control by means of the steam or air cylinder is independent of the main drive control.

Reference being made to the annexed drawings:

Fig. 1 is a side elevation of the improved machine, Fig. 2 is a left hand end elevation with gears removed. Fig. 3 is a detail view of these gears. Fig. 4 is a section on line 4—4 of Fig. 1. Figs. 5 and 6 are detail views of part of the cam mechanism. A represents the frame of the machine comprising the base A¹, two end members A² A³ these two members being bridged by and secured to the capping member A⁴. A base member A¹ and capping member A⁴ are provided with slide ways a a¹ respectively along which slide the two intermediate frame members A⁵ A⁶.

In bearings in the base of the machine is mounted the shaft B carrying at its outer end a clutch B¹¹, the counterpart of which is carried by a shaft B¹² carrying a spur wheel B¹ meshing with a pinion B² on the shaft of the electric driving motor B³. The shaft B also carries a chain wheel B⁴ geared by chain B⁵ to the chain wheel B⁶ on the shaft B⁷ of the non adjustable chuck C, this shaft also carrying the pinion B⁸ geared through the wheel

train B⁹ with a spur wheel B¹⁰ on the shaft 9¹⁶ carried in bearings in the capping member A⁴ and whence motion is taken to the various cams for giving feed motion to the flanging and other wheels operating on the work as 70 hereinafter described.

The adjustable chuck C¹ and its associated flanging and other rollers are carried by the sliding frame member A⁵, the shaft C² of the adjustable chuck C¹ being mounted in a bearing C³ in the member A⁵ and extending through the members A⁶ and A³ and carrying slidingly keyed upon it a chain wheel C⁴ mounted in the frame member A³ and geared by chain C⁵ to a chain wheel C⁶ keyed upon the shaft B.

Driving motion may thus be communicated to the two chucks C C¹ from the motor irrespective of the position of chuck C¹.

The frame member A⁶ is adjustable to and from the end member A³ by the following means. To the frame member A⁶ is attached a screw threaded rod D engaging a hand operatable nut D¹ mounted revolvably in the member A² but incapable of moving endwise 90 therein. By revolving this nut the member A⁶ may be moved from or to the end frame member A³ and thus adjusted in position with regard to the opposite end member A².

The frame member A⁵ is also movable to and from the member A⁶ and for ease of movement is preferably mounted on running wheels e e. The members A⁵ and A⁶ are connected by two toggles each consisting of two arms e² e³, e⁵ e⁶ respectively, pivoted at e⁴ e⁵ 100 e⁶ e⁷ respectively to the sides of members A⁵ A⁶. The knees of the two toggles are connected by a link e⁸. One of the arms e² of one of the toggles is connected to a lever e⁹, the other arm of which is connected to a piston rod e¹⁰. This piston rod is suitably guided as at e¹¹ and is operated by a piston in the cylinder e¹² carried on the side of frame member A⁶. Motive fluid may be admitted to said cylinder e¹² by means not shown the admission being regulated by a double acting valve operated by hand lever e¹³. The operation of the toggles e² e³ causes the frame member A⁵ to be moved towards or from the frame member A² according to the position of the hand lever e¹³ whereby the chucks C C¹ are caused to engage or disengage the drum.

For convenience in placing a drum in position to be engaged by the chucks a pair of curved bars f f (see Fig. 2) are pivoted on a shaft f¹ and extend from the front to below the centre line of the machine being curved down at the outer ends as at f² towards the floor.

Beneath the centre line of the chucks the bars f f have a transverse depression f⁴. A drum rolled up the slope f³ onto the bars f will rest temporarily in the depressions f⁴. The shaft f¹ carries a pedal lever f⁵. By depressing this pedal, the operator will cause

the drum held in the depressions f^4 to be lifted into alignment with the chucks C C¹ prior to the movement of member A⁵. After the drum has been seamed a similar movement of 5 the bars f f will permit the drum to be received again into the depression f⁴ when the member A⁵ recedes, and the seamed drum can then be rolled off the bars f onto the fixed rails f² and so discharged to the rear of the 10 machine.

Mounted to operate on the drum held between the chucks C C¹ are three rollers at each end, one set being carried by the fixed frame member A² and the other by the movable 15 frame member A⁵. These two sets are similar and a description of one of them will therefore suffice. Referring to Fig. 4, g is a curling roller, g¹ a flanging roller and g² a flattening roller. The rollers g g² are mounted 20 in blocks g⁵ g⁶ adapted to slide in guide ways g³ g⁴ radial to the axis of the chucks C C¹. To the blocks g⁵ g⁶ are pivoted screws g⁷ g⁸ on which are threaded sleeves g⁹ g¹⁰ to which are pivoted bell crank levers g¹¹ g¹² 25 having rollers running on cams g¹³ g¹⁴ respectively (see Fig. 6). The rollers are held to the cams by spring g¹⁵. The cams g¹³ g¹⁴ are carried by shafts g¹⁶ g¹⁷ to which motion is given as hereinafter described.

30. Loose on each shaft g¹⁶ g¹⁷ is also an arm g¹⁸ g¹⁹ respectively having at its end a roller g²⁰ g²¹ bearing against a cam g²² g²³ on the opposite shaft.

35. The arm g¹⁸ is connected by a link g²⁴ to a sleeve g²⁵ threaded on a screw threaded rod g²⁶ which carries the flanging roller g¹. The arm g¹⁹ is connected by a link g²⁷ to a sleeve g²⁸ threaded on a screw threaded rod g²⁹ which carries a supporting roller g³⁰ (Fig. 40 4). The arms g¹⁸ g¹⁹ are held to the cams by springs g³¹.

The shaft g¹⁶ is driven as aforesaid through the gear train B⁹ and the shaft g¹⁷ is driven from shaft g¹⁶ through gearing B¹⁰ B¹⁰⁰ (Fig. 45 3). On the transverse shaft g³² of this bevelled gearing is a cam g³³ operating upon a lever g³⁴ connected by rod g³⁵ to a bell crank lever g³⁶ which is connected by link g³⁷ to the releasing lever g³⁸ of clutch B¹¹ so that on 50 termination of each revolution of shafts g¹⁶ g¹⁷ the clutch B¹¹ is opened and the drive of the motor B³ is disconnected. The bell crank lever g³⁶ can also be operated by hand lever g³⁹ on the shaft thereof.

55. Contiguous to each clutch C C¹ is a releasing fork h h¹, pivoted at h² h³ respectively and having tails h⁴ h⁵ connected to each other by a rod h⁶. On retirement of the frame member A⁵ the chuck C¹ carried thereby will be moved to a position beyond that of the fork h¹ which will then bear against the end of the drum and reacting with the fork h will ensure the stripping of the drum from the chucks.

60. During the return or upward movement

of the flanging rollers g¹ in the flanging operation the supporting rollers g³⁰ are subjected to a considerable inward thrust which exerts a deflecting and bending stress on the carrier rods g²⁹ for the supporting roller spindles and thus deflecting said rollers out of a vertical plane of rotation. To take up the stress and strain of this inward thrust on the supporting rollers the spindles on said rollers are provided with telescoping 70 extensions arranged to permit the chucks to be brought into and out of receptacle supporting position, one of which extensions is adjustable to adapt said means for different lengths or depths of receptacle. For this purpose the spindles of one supporting roller has a threaded extension j² having threaded connection with one end of a sleeve j of a length less than the space between the spindles, and the spindle of the other supporting 75 roller is arranged with a similar extension threaded into one end of an adjusting sleeve and having a rod j¹ threaded into the opposite end also of a length less than the space between the spindles, the free end of which rod j¹ slidably engages in the sleeve j. By this arrangement the inward thrust on the supporting rollers is transmitted through the spindles thereof to the telescoping extensions j, j¹ of the spindles and taken up in such connection. 80

What I claim as my invention and desire to secure by Letters Patent of the United States is:—

1. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets each comprising a supporting roller, a curling roller and a flanging roller carried by said head stock and tail stock respectively above the axis of the chucks, and means carried by the capping member for operating said rollers. 100

2. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets each comprising a supporting roller, 105

a curling roller and a flanging roller carried by said head stock and tail stock respectively above the axis of the chucks and shafts carried by the capping member for operating 110

120

125

130

said rollers, a shaft in the base member, means for rotating the latter shaft, and gearing connecting the shaft in the base with the shafts in the capping member and the 5 shafts of the chucks.

3. In apparatus for automatically flanging and seaming the heads and bodies of sheet metal receptacles, the combination of a frame comprising a base member, two end members 10 and a capping member, one of said end members forming a head stock, a tail stock movable in said frame between the base and capping member, chucks, shafts for said chucks carried by said head stock and tail stock 15 respectively, means for rotating said chucks, two sets each comprising a supporting roller a curling roller, and a flanging roller carried by said head stock and tail stock respectively above the axis of the chucks, means 20 carried by the capping member for operating said rollers, a movable frame member adjustable in distance from one of the end frame members, toggles connecting said movable frame member and tail stock, and fluid 25 operated mechanism for moving the tail stock to and from said movable frame member.

4. In apparatus for automatically flanging and seaming the heads and bodies of sheet 30 metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets of rollers each set comprising 35 a supporting roller, a curling roller and a flanging roller carried by said head stock and tail stock respectively above the axis of the chucks, means carried by the capping member for operating said rollers, and means 40 to release the drum from the chucks as they recede from one another.

5. In apparatus for automatically flanging and seaming the heads and bodies of sheet 45 metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets of rollers each set comprising a supporting roller, a curling roller and a flanging roller carried by said head stock and tail stock respectively above the axis of the 50 chucks, means carried by the capping member for operating said rollers, and levers pivoted on said base member for lifting and lowering a drum with respect to the chucks.

6. In apparatus for automatically flanging 55 and seaming the heads and bodies of sheet

metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets of rollers each set comprising a supporting roller a curling roller and a flanging 70 roller carried by said head stock and tail stock respectively above the axis of the chucks, means carried by the capping member for operating said rollers, bars pivoted on said base member having depressions to receive a drum and formed as ramps, and a pedal for operating said bars for lifting and lowering a drum with respect to the chucks.

7. In apparatus for automatically flanging and seaming the heads and bodies of sheet 75 metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets of rollers each set comprising a supporting roller, a curling roller and a flanging 80 roller carried by said head stock and tail stock respectively above the axis of the chucks, shafts carried by the capping member for operating said rollers, a shaft in the base member, a clutch, means for rotating the shaft in 85 the base member through said clutch, gearing connecting the shaft in the base member with the shafts in the capping member and the chuck shafts respectively, automatic disengaging gear for said clutch operable by the shafting in the capping member, hand operable striking gear for said clutch, a movable frame member adjustable in distance from one of the end frame members, toggles connecting said movable frame member and tail 90 stock, fluid operated mechanism for moving the tail stock to and from said movable frame member, and drum releasing gear operative to detach the drum from the chucks as they 95 recede from one another.

8. In apparatus for automatically flanging and seaming the heads and bodies of sheet 100 metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, rollers carried by said head stock and tail stock respectively and movable towards the axis of said chuck from positions above the axis of the chucks, and means carried by the 105 capping member for operating said rollers.

9. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, rollers carried by said head stock and tail stock respectively and movable towards the axis of said chuck from positions above the axis of the chucks, shafts carried by the capping member for operating said rollers, a shaft in the base member, gearing connecting the shaft in the base member with the shafts in the capping member and with the chuck shafts.
10. 10. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, supporting rollers movable downwardly in the vertical plane of the chuck centres, curling rollers and flanging rollers movable obliquely downwardly towards the axis of the chucks means carried by the capping member for operating said rollers, and adjustable distance regulating means between the said supporting rollers.
11. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, supporting roller, a curling roller and a flanging roller carried by said head stock and tail stock respectively above the axis of the chucks and movable downwardly with respect to the chucks, shafts carried by the capping member for operating said rollers, a shaft in the base member, a clutch, means for rotating the shaft through said clutch, gearing connecting the shaft in the base with the shafts in the capping member, automatic disengaging gear for said clutch operatable by the shafting in the capping member, hand operatable striking gear for said clutch, a movable frame member adjustable in distance from one of the end frame members, toggles connecting said movable frame member and tail stock, means for moving the tail stock to and from said movable frame member, bars pivoted on said base member having depressions to receive a drum and formed as ramps, a pedal for operating said bars for lifting and lowering a drum with respect to the chucks, and drum releasing gear operative to detach the drum from the chucks as the chucks recede from one another.
12. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, supporting rollers movable downwardly in the vertical plane of the chuck centres, curling rollers and flanging rollers movable obliquely downwardly towards the axis of the chucks, shafts carried by the capping member for operating said rollers, a shaft in the base member, a clutch, means for rotating the shaft through said clutch, gearing connecting the shaft in the base with the shafts in the capping member, and automatic disengaging gear for said clutch operatable by the shafting in the capping member.
13. In apparatus for automatically flanging and seaming the heads and bodies of sheet metal receptacles, the combination of a frame comprising a base member, two end members and a capping member, one of said end members forming a head stock, a tail stock movable in said frame between the base and capping member, chucks, shafts for said chucks carried by said head stock and tail stock respectively, means for rotating said chucks, two sets of rollers each comprising a supporting roller, a curling roller and a flanging roller carried by said head stock and tail stock respectively above the axis of the chucks and movable downwardly with respect to the chucks, shafts carried by the capping member for operating said rollers, a shaft in the base member, a clutch, means for rotating the shaft through said clutch, gearing connecting the shaft in the base with the shafts in the capping member, automatic disengaging gear for said clutch operatable by the shafting in the capping member, hand operatable striking gear for said clutch, a movable frame member adjustable in distance from one of the end frame members, toggles connecting said movable frame member and tail stock, means for moving the tail stock to and from said movable frame member, bars pivoted on said base member having depressions to receive a drum and formed as ramps, a pedal for operating said bars for lifting and lowering a drum with respect to the chucks, and drum releasing gear operative to detach the drum from the chucks as the chucks recede from one another.
14. In apparatus for securing closures to sheet metal receptacles, rotatable chucks one of which chucks is movable relative to the other for releasably supporting a receptacle body with a flanged disk in the ends thereof, rollers arranged above the axis of the chucks for flanging laterally the contiguous portions of the flange of the closure disks and receptacle end, curling and flattening said flanged portions, and means arranged above said rollers for reciprocating said rollers in a direction toward and away from the axis of the chucks.
15. In apparatus for securing closures to sheet metal receptacles as claimed in claim 14, a support for a receptacle below the axis

of the chucks and operative to position a receptacle relative to and for the engagement of the chucks and receive a receptacle from the chucks.

5 16. In apparatus for securing closures to sheet metal receptacles, the combination of a supporting frame, a fixed head stock, a tail stock movable in the frame relative to the fixed head stock, chucks rotatably carried by 10 said stocks to support a receptacle body with flanged disks in the ends thereof, and fluid pressure operated means to move the tail stock relative to the head stock.

17. Apparatus for securing closures to 15 sheet metal receptacles as claimed in claim 16, wherein the fluid pressure operated means to move the tail stock comprises toggle links connected with said tail stock and a fixed part, fluid pressure cylinders, and pistons in said 20 cylinders connected with the toggle links.

18. In apparatus for securing closures to sheet metal receptacles, a pair of rotatable axially arranged chucks one of which chucks is movable axially relative to the other for 25 releasably supporting a receptacle body with flanged disks in the ends with the flanges thereof and receptacle ends in contiguous relation, rollers operative to flange the disk flanges and contiguous receptacle ends laterally, curl and flatten such flanged portions, and means to release the receptacle from the chucks as one recedes from the other.

19. In apparatus for securing closures to sheet metal bodies, a pair of rotatable axially 35 arranged chucks for releasably supporting a receptacle body with flanged disks in the ends, one of which chucks is axially movable toward and away from the other chuck, adjustable means for positioning one chuck relative 40 to the other, rollers operative to laterally flange the disk flanges and contiguous receptacle ends, curl and flatten said laterally flanged portions, said rollers being arranged above and having movement in a direction toward and away from the axis of the chucks, and a receptacle support below the axis of 45 the chucks and operative to position a receptacle thereon for engagement by the chucks and to receive a receptacle from the chucks.

50 20. In apparatus for securing closures to receptacle bodies, a frame embodying a pair of opposed members one of which is fixed and arranged with a head stock, and the other of said members adjustable toward and away 55 from the fixed member, and an intermediate member carrying a tail stock in opposed relation to the head stock, said intermediate member being movable toward and away from the head stock carrying member.

60 21. In apparatus as claimed in claim 20, means carried by the adjustable frame member and connected with the tail stock carrying member operative to move said latter member toward and away from the head stock 65 carrying member.

22. In apparatus for securing closures to receptacle bodies, a frame embodying a base, a pair of opposed end members, and a cap member secured to the end members in opposed relation to the base, a head stock carried by one of the end members, a member intermediate the end members and mounted on the base and cap member to have adjustment longitudinally thereof intermediate the end members, a member adjustably mounted 70 between the base and cap member between the intermediate and head stock carrying frame members, and a tail stock carried by said latter member.

23. In apparatus for securing closures in 80 the end of receptacle bodies as claimed in claim 25, wherein the inwardly directed members associated with the spindles of the supporting rollers to take up lateral inward thrust on the rollers comprises a rod connected to the spindle of one of the supporting rollers and a sleeve connected with the spindle of the other roller for slidable engagement of the rod, and said rod and sleeve being of a length less than the space between the roller carrying spindles, and one being adjustable to accommodate said thrust take up means to receptacles of different length.

24. In apparatus for securing flanged closures to the ends of receptacle bodies, a pair 90 of frame members carrying chucks for supporting a receptacle body with closures inserted in the ends thereof, one of which members is fixed and the other member movable toward and away from the fixed member, means operative to move the movable member toward and away from the fixed member, flanging, supporting, curling and flattening rollers carried by each of said frame members above the axis of the chucks, actuating 100 shafts for said rollers rotatably carried by said frame members and relative to which the movable frame member is longitudinally movable, and means associated with the spindles of the supporting rollers to take up the 105 stress and strain of the inward thrust on the supporting rollers during the flanging operation.

25. In apparatus for securing closures 115 in the ends of receptacle bodies, a fixed frame member rotatably carrying a receptacle supporting chuck, a frame member movable toward and away from the fixed frame member and rotatably carrying a receptacle supporting chuck co-axially of 120 the chuck carried by the fixed frame member, means operative to move the movable frame member and chuck carried thereby toward and away from the fixed frame member, flanging and supporting rollers supported by 125 said frame members to have movement in the direction of the plane of rotation of said rollers, and, inwardly directed members associated with the spindles of the supporting rollers arranged to take up the stress and 130

strain of the inward lateral thrust on the supporting rollers during the flanging operation.

26. Apparatus for securing closures in the ends of receptacle bodies as claimed in claim 5, wherein the means for taking up the stress and strain of the thrust on the supporting rollers comprises a sleeve connected with the threaded extension of the spindle of one of

said rollers, and a rod adjustably connected with the spindle of the other supporting 10 roller slidably engaging in the sleeve and adapted for sliding movement relative to each other.

In witness whereof I have signed this specification.

CHARLES JOSEPH RHODES.
